UNITED STATES PATENT OFFICE.

DAVID GRANT, OF CHICAGO, ILLINOIS.

ARCH SUPPORT.

Application filed September 24, 1921. Serial No. 502,939.

To all whom it may concern:

Be it known that I, DAVID GRANT, a citizen of the United States, residing at Chicago, in the county of Cook and State of Illinois, have invented new and useful Improvements in Arch Supports, of which the following is a specification.

This invention relates to an arch support and has for its primary object the construction of an arch support that has a proper degree of flexibility so as to properly conform to the arch of the foot instantly.

An object of the invention is the construction of an arch support that will give a spring action in walking and will tend to lift the foot as the latter is raised from the ground.

Another object of the invention is the construction of an arch so as to have oscillatory movement thereby allowing free action of the foot to give the maximum amount of comfort.

With these and other objects in view the invention will be better understood from the following detailed description taken in connection with the accompanying drawing wherein:

Fig. 1 is a top plan view.

Fig. 2 is a top plan view with the top section removed.

Fig. 3 is a plan view with the top section and spring plate removed.

Fig. 4 is a bottom plan view.

Fig. 5 is a longitudinal sectional view.

Fig. 6 is a cross sectional view.

Fig. 7 is a plan view of the spring plate.

Fig. 8 is an enlarged detail sectional view illustrating how the tongue is supported to accommodate oscillatory movement of the spring plate.

Again referring to the drawings illustrating one of the many constructions of my invention the numeral 1 designates the base plate shaped to conform to the interior of a shoe and provided with spaced slots 2. It will be noted that these slots extend at an angle to each other for a purpose herein-after described. Riveted to the undersurface of the plate 1 directly under the slots are clips 3 each provided with a shoulder 4. The numeral 5 designates a spring plate that is provided with a flange 6 for engagement against the side of the arch portion of the foot. This plate 5 is further provided with inclined edges 7 from which project tongues

8. Each tongue is of a shape to be slipped through the slot 2 and is provided with a curved edge 9 that bears directly upon the heretofore mentioned shoulder 4. From this construction it will be seen that the blade can be slightly bowed for allowing the insertion of the tongue 8 through the slots thereby giving the proper resilient action to the plate 5. It will also be noted by referring to Figure 8 that the curved edge 9 of the tongue bears directly against the shoulder in a manner to space the edge 7 a slight distance from the base plate thereby allowing oscillatory movement of plate 5, thereby greatly relieving the foot of the user and besides properly distributing the weight. The clip 3 eventually receives the entire weight thereby bringing into proper play the ball and heel of the foot. It will be further seen that by using different sizes of plate 5 the arch effect can be increased or decreased for accommodating different size arches.

Riveted to the plate 1 is a bottom section 10 that is provided with openings 11 for accommodating the clip. The upper section of the base plate 1 as well as the spring plate 5 is covered by the top section 13 that is riveted to the base plate as indicated at 12 so that the top section may be raised from one end to allow the substitution of different size spring plates.

It is, of course, to be understood that the various plates and sections may be given other shapes than illustrated and may be associated in other relations without departing from the spirit of my invention and, therefore, I do not desire to be limited in any manner except as set forth in the claims hereunto appended.

Having thus described my invention what I claim is:

1. An arch support comprising a base plate having spaced slots, clips arranged adjacent the slots, and a second plate having tongues passed through the slots each having a curved surface arranged in engagement with the clip.

2. An arch support comprising a base plate having spaced slots, a spring plate having tongues adapted to be inserted in said slots, and clips secured to the base plate and engaging said tongues in a manner to allow oscillatory movement of the spring plate.

3. An arch support comprising a base plate having spaced slots, clips secured to the base plate directly under said slots and each provided with a shoulder, and an arched spring plate having tongues projecting from the ends thereof inserted through said slots and bearing against said shoulder.
4. An arch support comprising a base plate having spaced slots, clips secured to the base plate directly under said slots and each provided with a shoulder, an arched spring plate having tongues projecting from the ends thereof inserted through said slots and bearing against said shoulder, said tongues being curved where they engage said shoulder, a bottom section of flexible material secured to the base plate, and a top section of flexible material covering said spring plate.
5. In an arch support to be positioned within a shoe, a base plate, clips carried thereby, and a resilient supporting plate arched in the direction of its length away from the base plate and provided with terminal elements engaging with the clips and coacting therewith to removably secure the supporting plate to the base plate.
6. In an arch support to be positioned within a shoe, a base plate, clips carried thereby, and a resilient supporting plate arched in the direction of its length away from the base plate and provided with terminal elements engaging with the clips and coacting therewith to secure the supporting plate to the base plate, the clips including abutment elements disposed to contact with the terminal elements of the supporting plate to limit extension thereof, the ends of the terminal elements adjacent said abutment elements being rounded and permitting rocking movement of the supporting plate relative to the base plate.

In testimony whereof I affix my signature.
DAVID GRANT.
